UNITED STATES PATENT OFFICE

2,550,627

METHOD OF MAKING FLOOR AND ROOF CONSTRUCTIONS

Ernest Walter, Montclair, N. J., assignor to Porete Manufacturing Company, North Arlington, N. J., a corporation of New Jersey

Application November 4, 1947, Serial No. 784,060

11 Claims. (Cl. 25—155)

1

The present invention is directed to a method of making mechanical structures such as floor and roof constructions, more particularly those involving concrete beams and slabs.

It is quite desirable in systems of this kind to reduce the weight thereof while obtaining adequate strength in the concrete elements of which such structures are formed. In order to do this, it has been common practice to utilize filler blocks which were set up on false flooring and the structural concrete poured between the same to form beams. Such filler blocks were often made of a lightweight mixture of wood fiber and cement and were produced at a central point or factory. It was impractical to produce them at the point of use and therefore it was necessary to pack such blocks and ship the same. Various other types of filler blocks were used, such as hollow clay tile and concrete tile which have considerable strength but such blocks are fragile and in the handling and transportation, a very substantial amount of breakage occurred. Also, it required considerable care and labor to properly place the same in position.

Metal pans or domes have also been used in place of filler blocks. Sometimes they were allowed to remain in place after the concrete had set or they were removed. When they were removed, this required extra labor and care not to damage them; in addition, they had to be cleaned and oiled again. With metal domes, it was necessary to provide a metal lath ceiling in order to obtain a smooth under-surface when plaster was applied.

The present invention is intended and adapted to overcome the difficulties and disadvantages inherent in prior structures of this type, it being among the objects of the present invention to provide a method of making a floor or roof construction of the type described wherein all of the filler blocks and of the structural parts are fabricated in the field and transportation and erection of fragile elements is avoided.

It is also among the objects of the present invention to provide a method of making a lighter structure having improved acoustic properties, better heat insulation and a high degree of fire resistance.

It is further among the objects of the present invention to provide a method of making a structure of the type described which is relatively simple, which may be readily and quickly erected and which requires workmen of only moderate skill for adequate results.

It is still further among the objects of the pres-

ent invention to provide a method of making a structure of filler blocks which is better adaptable to various conditions, as spans, loads to be carried, single and continuous designs, and one- or two-way systems.

In practicing the present invention, there is provided a false floor form or support, on which there is placed a series of box-like forms which have the shape and are in the position of the beams which are to be later formed. After such forms are in place, there is provided a highly porous, cellular or light concrete mixture which is poured on the floor between the box-like forms. This structure replaces the prior art filler blocks. After the porous concrete has set, the forms are removed which can be readily accomplished because they are suitably tapered and then structural concrete is poured into the spaces occupied by the forms whereby the beams of the structure are produced, and in the same operation a layer of concrete is poured over the entire surface.

The porous concrete used has a weight which is not over 50 lbs. per cubic foot and preferably the weight is from 15 to 30 lbs. per cubic foot. Even lighter weight concrete can be used but there is danger of damage thereto by the workmen treading thereon in the fabrication of the remainder of the structure. The lightweight concrete is preferably one in which cement with or without a small amount of suitable fiber such as wood fiber, excelsior, asbestos or the like, is mixed with water and a foaming agent, such as saponin or the like, and poured between the form boxes. Other methods of obtaining the lightweight concrete may be by using, for instance, aluminum powder in the mix, thus producing a gas by chemical reaction and an expansion of the mass of concrete. There may also be used a light aggregate such as vermiculite in the cement mixture. The porous cellular concrete has uniformly dispersed therethrough closed cells filled with gas or air, the cells being usually less than one-eighth inch in diameter, and the concrete will float in water.

In the accompanying drawing constituting a part hereof and in which like reference characters indicate like parts,

Fig. 1 is a fragmentary perspective view somewhat diagrammatic in nature, illustrating one mode of operation of the invention;

Fig. 2 is a vertical cross-sectional view taken along the line 2—2 of Fig. 1;

Fig. 3 is a view similar to Fig. 2, showing the porous concrete in position and the forms removed;

3

Fig. 4 is a similar view showing the next stage of the operation with the structural concrete in place;

Fig. 5 shows the final step with the false flooring removed;

Fig. 6 is a vertical cross-sectional view similar to Fig. 2, showing a modification wherein the box-like form is supported above the false flooring;

Fig. 7 is a view similar to Fig. 6, showing a further modification thereof;

Fig. 8 is a vertical cross-sectional view of a structure made with the forms of Figs. 6 or 7;

Fig. 9 is a view similar to Fig. 1, showing a modification wherein beams and cross-beams are formed in the structure;

Fig. 10 is a vertical cross-sectional view of a structure made by a further modification of the box-like forms;

Fig. 11 illustrates the completed structure of Fig. 10;

Fig. 12 is a fragmentary elevational view of a modified form of the invention showing different means for retaining the box-like forms on the false floor;

Fig. 13 is a view similar to Fig. 12 showing a further modification;

Fig. 14 is a detail view of a form of pin used in the construction of Fig. 13, and

Fig. 15 is a fragmentary vertical cross-sectional view of a modified form, some parts being shown in elevation.

Referring to Figs. 1 to 5 inclusive, there is provided a false floor form 1 held on suitable supports 2 and held in any desired manner in position as by being supported by walls 3 or by upright members extending from the floor below.

Each of the box-like forms may consist of side members 4 and 5 tapered downwardly and inwardly to allow withdrawal thereof from the concrete and a bottom member 6 joining the side members. These forms need not be of uniform width throughout and may be widened as shown at 7 near the walls 3 to provide a greater cross-section of structural concrete to more adequately support the load. A series of such forms may be joined by end members 8 to complete the forms and provide spaces 9 between the same. Lightweight concrete 10 as described above, is poured into spaces 9 and is allowed to set. Then the forms are removed by raising members 4 and 5 which can be withdrawn very readily due to the taper thereof leaving spaces 11 between blocks 10. Concrete 12 is then poured over blocks 10 filling spaces 11 and forming beams 13 which are suitably supported on walls 3.

With reference to Figs. 6, 7 and 8, the box-like forms may be provided with top closing members 14 in order to avoid the possibility of lightweight concrete accidentally entering the same and also to strengthen the structure of the form. A series of pins or nails 21 driven through the bottom 6 of the forms provides means whereby said forms are supported on floor 1 out of contact therewith.

In Fig. 7 there is shown a metal form made of sheet material wherein the sides 15 and 16 are tapered downwardly and inwardly and are integral with the bottom 17. A metal cover 18 is provided over the top and is crimped around the side to complete the form. One or more plates 19 having legs 20 are placed upon floor 1 and the forms placed on said plates. When the lightweight concrete is poured in place as shown in Fig. 8, it forms blocks 22 with connecting portions 23 giving a smooth ceiling and uniform

texture. Then the forms of Fig. 6 or 7 are removed, the reinforcing bars 13' are placed into the proper position, and the structural concrete poured in place to form both the floor slabs and the beams in a unitary structure. Plates 19 usually remain in the structure and add reinforcement thereto in addition to the usual reinforcements contained in the structural beams.

When both beams and cross beams are to be formed, there is provided a series of box-like forms 4, as shown in Fig. 9, in parallel arrangement. There are also provided transverse forms having side members 24 and 25 tapering downwardly and inwardly, the ends thereof being so shaped as to conform with the sloping sides of forms 4. Transverse end forms have sloping sides 24' and 25' with one shaped end conforming with form 4 and the other end made in any desired manner to conform with the rest of the structure. In making the assembly of forms, 24'-25' may be set in place, adjacent form 4 placed in contact therewith, then form 24-25 placed in contact with the same and so on until all the forms are in place.

Then lightweight concrete is poured into a substantially rectangular space 26 to form blocks 27. After they have been set, forms 4 are lifted out, giving access to forms 24-25 and the like, which may then be removed. This gives a structure as shown at the left-hand side of Fig. 9 having longitudinal spaces 28 and transverse spaces 29 between blocks 27. Structural concrete is then poured to fill all of the spaces and also to form a unitary floor slab.

In Figs. 10 and 11 is shown a modification of the invention which eliminates the necessity for false flooring 1. There is provided a series of plates 30, preferably of metal, which take the place of said floor. Each of the box-like forms has double sides 31-32 joined at the top and diverging so as to leave the space 33 at the lower end thereof and between the same. A flange 34 formed on member 31 acts as a support for plate 30. Integral with member 32 is bottom 35 completing the false flooring and this in turn is integral with member 36 of the other side of the box-like form. Said side also includes a second member 37 integral with 36 and diverging therefrom at the bottom to provide space 38. A flange 39 on member 37 provides means for holding an adjacent plate 30 in position. Such a form may be supported in any desired manner and is of sufficient strength so as to carry the dead load of concrete but need not be sufficiently strong to carry any live load. Lightweight concrete 40 is then poured into position on plates 30 and allowed to set. Structural concrete 41 is then poured into place and forms both a floor slab and beams 42. When the concrete has completely set, the box-like forms may be removed by springing the metal of the double side walls together and pulling downwardly, thereby taking with them the intermediate plates 30. The final structure as shown in Fig. 11 may have its underside plastered over and the spaces defining the beams will become filled with plaster and give a uniform appearance of ceiling.

Fig. 12 shows another way of erecting the temporary forms for the lightweight concrete filler blocks. By using long steel sheets 4 and 5, which are bent towards each other at the bottom as shown at 43 and 44, and tacking these sheets to the false wood forms with double headed nails 45 that can be pulled out easily. Thereby, a very simple and adaptable form can be made which

can easily be widened at the ends where required. Because the lightweight fill when poured wet weighs about one-half as much as water, the pressure against the sides is very little so that thin sheets may be used.

Fig. 13 shows another way which has been found to be practical for one story buildings where it would be too expensive to provide special forms. Pins 46, as shown in Fig. 14, have parallel pins 47 attached to the upper part thereof to form a slot 48 therebetween. These pins are driven at regular intervals into the false floor. It has been found that a lightweight cardboard made of high wet-strength paper which is put into these slots forms a very adaptable form for the lightweight concrete fill. These paper boards can either be removed when the lightweight concrete fill is set and thrown away, or they may be left in the concrete as a separator between the lightweight and the structural concrete.

There are numerous advantages resulting from the present invention. For instance, the building may be erected much more quickly and with less labor than heretofore. Variations in the shape and sizes of beams are much more readily produced by the present invention than where pre-cast blocks or a limited number of forms are used. The cost of building a floor or roof according to the present invention is substantially less than by the old methods. The lightweight concrete can be mixed and poured with the use of the same equipment and the same labor unions as are used in providing the structural concrete. The lightweight concrete made with a foam-producing material does not require special materials or equipment, but utilizes Portland cement with a small amount of wood or vegetable fiber or the like.

The box-like forms are simple to make and are easy to maintain. They are economical in use in that they may be used over and over again for similar designs of structures.

If the system described in connection with Figs. 10 and 11 is used, the whole floor construction may be made without using any false work and no support from the floor below is necessary. Because of the excellent bond between the lightweight and the structural concrete, the whole structure becomes a unitary mass.

Where a sound absorbing ceiling is necessary and acoustical blocks are used, these may be laid on the false floor and the box-like forms placed thereon, thereby providing as a single unit, an acoustical ceiling and a floor structure. The present type of construction is adapted not only to multi-story buildings but also to one or two floor residences where a fireproof and sound proof first floor over a basement is desired.

Although the invention has been described setting forth several specific embodiments thereof, such examples are intended to illustrate the invention and not to limit the same as many variations in the details may be made within the spirit of the invention. For instance, the false floor may be supported from the walls, from the lower floor, or otherwise. The materials of construction may be varied and modified and in some instances such materials as magnesia cement, mixtures containing gypsum and other binders may be used. The several forms may be of suitable material such as wood, synthetic board, metal and the like and the parts thereof may be foldably assembled or hinged together.

In some cases, as shown in Fig. 15, the box-like forms may be omitted and the equivalent

effect obtained by pouring the lightweight concrete 10 to a uniform thickness over the entire false floor area 1. After the concrete has become set, grooves 52 and 53 for the structural concrete beams may be cut out as with a circular saw or carborundum wheel 50 on shaft 51 and the surplus material 54 removed. The spaces 55 so obtained are in effect box-like forms and the structural concrete is cast into the same, as fully described above.

These and other variations in the details of the structure may be made within the principles herein set forth and the claims are therefore to be broadly construed and not to be limited except by the character of the claims appended hereto.

I claim:

1. A method of making a floor or roof structure which comprises erecting a false floor form, placing thereon longitudinally extending box-like forms of the shape and in the position of the beams of said structure, pouring a cellular concrete on said floor form between said box-like forms and allowing the same to set, removing said box-like forms, pouring structural concrete into the resulting spaces, and allowing the same to set.
2. A method of making a floor or roof structure which comprises erecting a false floor form, placing thereon longitudinally extending box-like forms of the shape and in the position of the beams of said structure, pouring a cellular concrete on said floor form between said box-like forms and allowing the same to set, pouring structural concrete into the resulting spaces, and allowing the same to set.
3. A method of making a floor or roof structure which comprises erecting a false floor form, placing thereon longitudinally extending box-like forms of the shape and in the position of the beams of said structure, the bottom of said box-like forms being above the surface of said floor form to provide a uniform cast ceiling, pouring a cellular concrete on said floor form between said box-like forms and allowing the same to set, removing said box-like forms, pouring structural concrete into the resulting spaces, and allowing the same to set.
4. A method of making a floor or roof structure which comprises erecting a false floor form, placing thereon longitudinally extending box-like forms of the shape and in the position of the beams of said structure, pouring a cellular concrete on said floor form between said box-like forms and allowing the same to set, removing said box-like forms, introducing reinforcing members and then pouring structural concrete into the resulting spaces, and allowing the same to set.
5. A method of making a floor or roof structure which comprises erecting a false floor form, placing thereon longitudinally extending box-like forms of the shape and in the position of the beams of said structure, the sides of said box-like forms being tapered downwardly to facilitate withdrawal thereof after concrete has set, pouring a cellular concrete on said floor form between said box-like forms and allowing the same to set, removing said box-like forms, pouring structural concrete into the resulting spaces, and allowing the same to set.
6. A method of making a floor or roof structure which comprises erecting a false floor form, placing thereon longitudinally extending box-like forms of the shape and in the position of the beams of said structure, pouring a cellular concrete on said floor form between said box-like forms and allowing the same to set, said concrete

being a mixture of cement, a foaming agent and water, removing said box-like forms, pouring structural concrete into the resulting spaces, and allowing the same to set.

7. A method of making floor or roof structure which comprises erecting a false floor form, pouring a cellular concrete on said floor and allowing the same to set, forming longitudinally extending box-like forms of the shape and in the position of the beams of said structure within said cellular concrete, pouring structural concrete into the resulting spaces, and allowing the same to set.

8. A method of making floor or roof structure which comprises erecting a false floor form, pouring a cellular concrete on said floor and allowing the same to set, forming longitudinally extending box-like forms of the shape and in the position of the beams of said structure within said cellular concrete by cutting and removing portions of said porous concrete, pouring structural concrete into the resulting spaces, and allowing the same to set.

9. A method of making a floor or roof structure which comprises erecting a false floor form, placing thereon longitudinally extending box-like forms of the shape and in the position of the beams of said structure, pouring a cellular concrete on said floor form between said box-like forms and allowing the same to set, placing reinforcing members into the spaces between said porous concrete elements, pouring structural concrete into the resulting spaces, and allowing the same to set.

10. A method of making a floor or roof structure which comprises erecting a false floor form, placing thereon longitudinally extending box-like forms of the shape and in the position of the beams of said structure, pouring a cellular con-

crete on said floor form between said box-like forms and allowing the same to set, removing said box-like forms, placing reinforcing members into the spaces between said porous concrete elements, pouring structural concrete into the resulting spaces, and allowing the same to set.

11. A method of making a floor or roof structure which comprises erecting a false floor form, placing thereon longitudinally extending box-like forms of the shape and in the position of the beams of said structure, pouring a cellular concrete on said floor form between said box-like forms and allowing the same to set, removing said box-like forms, pouring structural concrete into the resulting spaces, and allowing the same to set, said box-like forms including vertically placed sheets with means for securing the same to said floor.
